UNITED STATES PATENT OFFICE.

CHARLES ARTHUR NICHTHAUSER, OF NEW YORK, N. Y.

DESIGN FOR A PURSE.

55,192.

Specification for Design.

Patented May 18, 1920.

Application filed September 20, 1919. Serial No. 325,279. Term of patent 3½ years.

To all whom it may concern:

Be it known that I, CHARLES A. NICHTHAUSER, a citizen of the United States, residing at New York, borough of Manhattan, in the county and State of New York, have invented a new, original, and ornamental Design for a Purse, of which the following is a specification, reference being had to the accompanying drawing, forming part thereof.

The figure is a front view.

I claim:

The ornamental design for a purse, as shown.

CHARLES ARTHUR NICHTHAUSER.
